CHARLES L. LOWMAN, OF LOS ANGELES, CALIFORNIA

TILTED BALANCE BOARD FOR GYMNASIUM USE

Application filed July 11, 1927. Serial No. 204,870.

My invention is a tilted balance board for gymnasium use especially intended to give corrective exercises of different types.

An object of my invention is a tilted balance board to aid in the correction of faulty posture, to give the proper bearing and carriage to the person taking the exercise, and to aid cases of flat feet, pronated ankle, and other distortions of the legs, twists and deviations from the normal. A further object of my invention is to affect the action of the brain of the person taking the exercise so that a mental hazard in regard to the balance may be changed to suit the particular person taking the exercise, and so that in taking different exercises when standing on the board the balancing centers will unconsciously be controlling the various muscles which are insufficiently developed.

In constructing my invention I utilize a pair of longitudinal boards which are spaced slightly apart and inclined downwardly and outwardly from each other, similar to the ridge of a roof, and between these boards I may have a vertical board to guide the person using my apparatus for exercising. This vertical board, however, is removable. In connection with the longitudinal boards of the balance, I utilize a number of different supports for the ends of the boards so that these ends may be raised to different elevations above the floor, so that perhaps one end may be on the floor level and the other at a considerable elevation. In addition, I may use one of the supports of any desired height and mount the balance boards as a teeter in order that the development of motor skill may still further be increased.

To utilize with these boards I have a series of steps which are made with treads inclined outwardly and downwardly from a central ridge. These steps may be placed at the high end of the inclined board in order that a child with weak feet may not have to jump to the floor from the high end of the incline. The steps may be placed back to back and give the corrective exercise by a person walking up one set of steps and down the other to increase skill in balance. In addition to the above features, the support-

ing boards on which the persons taking the exercises walk may be adjusted in inclination.

My invention is illustrated in the accompanying drawings, in which:

Figure 1 is a perspective view showing one manner of using my balance board.

Figure 2 is a side elevation of the board mounted on supports.

Figure 3 is an end elevation in the direction of the arrow 3 of Fig. 2.

Figure 4 is a side elevation of one of the balancing boards without supporting blocks.

Figure 5 is a side elevation showing my board used in connection with a set of steps.

Figure 6 is a side elevation showing the board mounted on a central supporting block and used as a teeter.

Figure 7 is a perspective view of a pair of steps placed together.

Figure 8 is a section through one of the boards, illustrating the manner of adjusting the inclination of same.

Figure 9 is a perspective view of a suitable pin for fastening the board to the supporting blocks or trestles.

The construction of the balancing board is substantially as follows:

A pair of end blocks 11 are utilized for each board, these preferably having a flat base 12, side edges 13 at right angles to the base, and inclined upper surfaces 14, these being on an inclination upwardly and inwardly towards each other. The extreme top surface 15 may be flat and parallel to the base. The blocks preferably have parallel front and rear sides 16 and have an enlarged bore 17 therethrough extending from side to side.

In a simple construction the supporting boards 18 on which the person taking the exercise walks and stands may be rigidly secured to the inclined surfaces of the end blocks 11, and the upper edge is spaced apart so that a vertical board 19 may be placed in the slot 20 between the two boards 18. If it is desired to adjust the angles of these boards, studs, or the like, 21, may be secured to the end blocks 11 and have adjusting screws 22 threaded therethrough, these screws engaging with brackets 23 on each end of each of

the boards 18, thus changing the transverse inclination of these boards, in which case it would be necessary to have hinges 24 connecting the boards to the blocks 11.

5 I have found it satisfactory to use balance boards with an over-all length of 8 feet, ten feet or twelve feet. The end blocks 11 have been made 6 inches from side to side and about 2 or 3 inches in longitudinal measurement. The lowest edge of the upper surface 10 of the inclined boards 18 has been made 2 $\frac{3}{4}$ inches and the upper edge 3 $\frac{3}{4}$ inches, thus giving a slope of one inch. The insertable or removable board or ridge 19 has its top 4 $\frac{3}{4}$ inches above the base of the end block 11 and this ridge board may be about $\frac{3}{4}$ of an inch 15 in thickness.

The supporting stands or trestles are designated generally by the numeral 25. These 20 have a relatively wide base 26 which is flat and intended to rest on the floor. The sides 27 are upwardly and inwardly inclined at a slight angle. The forward and rearward sides 28 also have a slight upward and inward inclination. The top of these stands 25 has a cut-out section 29, leaving lugs 30 at each end and through these lugs there are bores 31 in alignment.

One manner of using my balance board is 30 illustrated in Fig. 4 in which the board is placed so that its own supporting end blocks 11 rest directly on the floor, in which case the surface of the inclined boards 18 at its lower edge would preferably be from 2 to 4 35 inches above the floor.

For another type of exercise the board may be placed at an inclination, as shown in Fig. 5, in which one end rests on the end blocks 11 and the other on the supporting stand at the 40 desired elevation, or as shown in Fig. 2, the supporting stands may be of different heights so that the persons taking the exercises may walk up and down these boards or may stand on the boards, at the desired height above the 45 ground. I find it satisfactory to have the supporting blocks in three different heights, approximately 6 inches, 12 inches and 24 inches.

It is desirable to have center blocks 32 50 similar to the end blocks 11 and with a similar bore extending from side to side, except that these are slightly less in height. By this construction the balancing board may be mounted as a teeter, as shown in Fig. 6, having a center block 32 pivoting on a pin 33, in 55 order that in taking exercises a person may walk up an inclination until he comes to the center support and then tilt the board in the opposite direction and then walk down the inclination, or if desired, two people may exercise 60 on opposite ends of the balancing board.

In connection with my balancing board I utilize a set of steps, indicated generally by the numeral 34 (Figs. 5 and 7). In the construction shown I illustrate each set of steps 65 as having a block with a flat base 35 and a

vertical end 36 so that two sets of steps may be placed end to end. The treads 37 of each of the sets of steps have surfaces 38 at an inclination to each other, meeting in a ridge 39.

In the construction shown I have illustrated 70 three treads for each of the sets of steps and three risers, but it is to be understood that these may be made of any height, with any desired number of steps. The person taking the exercise may walk up one set 75 of steps and down the other, as illustrated in Fig. 7, or as illustrated in Fig. 5 they may walk up the inclined part and down the set of steps, or vice versa.

The use of my balance board and the other 80 appliances utilized therewith is believed to be obvious to those familiar with corrections 35 in disturbances of balance, deformities of the feet and legs, faulty posture, etc. However, it may be stated that for beginners it is desirable to utilize the center removable board 19 and to have the board close to the floor, or to use treads of less inclination or covered with rubber matting. They may then stand on this board and take various calisthenic exercises. As improvement develops, the balance board 90 may be elevated on one or more of the supporting stands and given different heights. In a further development in exercises, the center ridge board 18 is removed and the persons 95 taking the exercises are required to keep their balance without the aid of this board guiding the movements of their feet. In one form of exercises, the patient walks lengthwise of the board with a weight on his head and should not look down at his feet, but is 100 guided by the feel of the boards to the foot, and by noting when looking straight ahead, the slot between the two boards.

The steps, on account of having their treads 105 tilted, give or afford the board for the same type of exercises as the balance board and are intended to be utilized therewith, as in the manner above described, or in any other suitable way which will suggest itself to the 110 physician or technician prescribing the exercise.

The feature of having the exercising boards 115 with the outward and downward inclination and also the steps having a similar tread, is not merely to tilt the feet outwardly but the action of a person standing or walking on such board or steps causes an outward rotation of the leg to throw the muscles in balance. A purpose of the invention is to 120 develop a proper functional standing position to throw the muscles of the leg and trunk in such a position as to obtain proper coordination and balance.

Various changes may be made in the principles 125 of my invention without departing from the spirit thereof, as set forth in the description, drawings and claims.

I claim:

1. In an exercising device a balance board 130

comprising a pair of boards spaced apart longitudinally, each of said boards being inclined downwardly and outwardly from the center, and a spacing board extending vertically between the inner edges of the inclined boards and means to immovably support said boards.

2. In an exercising device, a plurality of end blocks having upper downwardly and outwardly inclined surfaces, a pair of boards extending longitudinally and connected at their ends to the said upper inclined surfaces, the inner edges of said boards being spaced apart.

3. In an exercising device, the combination of a pair of end blocks having upper downwardly and outwardly inclined top surfaces, a pair of boards extending between said blocks, the boards being outwardly and downwardly inclined, said boards being spaced apart, and a vertical spacing board between the inner edges of said inclined boards.

4. In an exercising device, a stand having a cut-out section with a pair of lugs on each side of the cut-out section, a block, a pair of boards secured to said block, said boards having their upper surfaces inclined outwardly and downwardly in a transverse direction, and a pin through the lugs and through the said block.

5. In an exercising device, the combination of a plurality of stands each having upper cut-out sections with a pair of lateral lugs with holes therethrough, a plurality of end blocks having upper outwardly and downwardly inclined surfaces, a pair of boards having their ends secured to said blocks, the inner edges of said boards being spaced apart, and said blocks having holes therethrough and a pin fitting through the holes in the lugs and the holes in the blocks.

6. In an exercising device, the combination of a stand having a cut-out section in its top with lateral lugs and holes through said lugs, an end block having outwardly and downwardly inclined upper surfaces, a pair of boards secured to said inclined surfaces, the inner edges of the board being spaced apart, the block having a pin therethrough, said pin engaging the holes in the lugs, a structure having a flight of steps, the treads of the steps being inclined outwardly and downwardly in a transverse direction the inclination of the steps and the boards being substantially the same to force the feet of the person exercising into the same position when on the steps and the boards.

7. In an exercising device, the combination of a plurality of stands, said stands having a pair of lugs on opposite sides adjacent the top, a plurality of blocks each having its upper surface downwardly and outwardly inclined, a pair of boards secured to said inclined surfaces, the boards being spaced apart and having a detachable vertical board in the said

space, the lugs having holes therethrough, and there being holes in the blocks and pins fitting in said holes connecting the stands and the blocks.

8. In an exercising device, as claimed in claim 7, a structure having a flight of steps, said steps having boards inclined downwardly and outwardly considered transversely thereof the inclination of the steps and the boards being substantially the same to force the feet of the person exercising into the same position when on the steps and the boards.

9. In an exercising device, the combination of a plurality of blocks, each having upper downwardly and outwardly inclined surfaces, a pair of boards pivotally connected to said surfaces, and means interconnecting the blocks and the boards to adjust the inclination of the boards.

10. In an exercising device, the combination of a plurality of blocks, each having upper outwardly and downwardly inclined top surfaces, a pair of boards connected to the inclined surfaces by a hinge connection at the upper and inner corners of the boards, said boards being spaced apart, and a vertical separating board in the said space, and means interconnecting the block and the boards to adjust the inclination of said boards.

11. In an exercising device, the combination of a pair of balance boards spaced apart laterally each being inclined downwardly and outwardly in a transverse direction from each other, and means to removably support said boards with the longitudinal axis substantially horizontal or slightly inclined thereto, whereby a person may walk on the board with the feet spaced apart.

In testimony whereof I have signed my name to this specification.
